[57] CLAIM

The ornamental design for a calendar holder, as shown and described.

DESCRIPTION

FIG. 1 is a top, front and right side perspective view of a calendar holder showing my new design with a calendar inserted for clarity of illustration only;

FIG. 2 is a top, front, and right side perspective view of the calendar holder;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top view thereof;

FIG. 8 is a bottom view thereof;

FIG. 9 is a sectional view taken along line 9—9 of FIG. 3; and,

FIG. 10 is a greatly enlarged top, front and right side perspective view thereof, as shown in FIG. 2.

The broken lines shown are for illustrative purposes only and form no part of the claimed design.
